WIND DIRECTION INDICATOR

Paul A. Odegard, 183 Box Mountain Drive,
Vernon, Conn. 06086

Filed July 5, 1972, Ser. No. 269,197

Term of patent 14 years

Int. Cl. D10—04

U.S. Cl. D52—6 D

FIG. 1 is a front perspective view of a wind direction indicator showing my new design;

FIG. 2 is a right side elevational view thereof;

FIG. 3 is a rear elevational view thereof; and

FIG. 4 is a bottom plan view thereof with the support arms out-away for ease of illustration.

I claim:

The ornamental design for a wind direction indicator, substantially as shown and described.
